UNITED STATES PATENT OFFICE.

PAUL T. ULRICH, OF MIAMI, FLORIDA.

KEY-FASTENER.

1,303,133.

Specification of Letters Patent. Patented May 6, 1919.

Application filed June 19, 1917. Serial No. 175,617.

To all whom it may concern:

Be it known that I, PAUL T. ULRICH, a citizen of the United States, and resident of Miami, in the county of Dade and State of Florida, have invented certain new and useful Improvements in Key-Fasteners, of which the following is specification.

This invention relates to the class of locks and latches and has particular reference to new and useful improvements in key fasteners.

The primary object of my invention is to provide a device of the character mentioned that is hingedly secured to a door knob and adapted to be detachably associated with the key.

For the purpose of illustrating my invention, I have shown in the accompanying drawings one form thereof which is at present preferred by me, since the same gives in practice satisfactory and reliable result, although it is to be understood that the various instrumentalities of which my invention consists can be variously arranged and organized and that my invention is not limited to the precise arrangement and organization of these instrumentalities as herein shown and described.

Other novel features of advantage and construction will more clearly hereinafter appear in the detailed description herein.

In the accompanying drawings:

The view is a perspective showing my invention applied to a door knob with the key in locked position.

The illustrative form comprises a spring wire ring member designated 10 which is adapted to hang loosely about the handle 11 of the door knob 12, in order that the same may be removed when it is desired.

The escutcheon plate 13 is provided with a key hole 14 in which a key 15 is insertible and as shown in the drawings, is arranged in a locked position. A key engaging member designated generally by the numeral 16 has the upper part of its barrel-like body portion formed with an opening 17 for loosely accommodating the ring member 10 so that the member 16 will be suspended from the ring member. A spring pressed pawl 18 is

slidably mounted in the opposite end of the body portion of the member 16 and is designed to removably close the hook-like engaging end 18' of the body portion, being operable by means of the knob 19. 55

The operation of my invention is as follows: After the key member has been inserted in the lock member, and locked the fastener is secured thereto which will retain the same in rigid position and prevent any one on the outside from removing the key. Furthermore my invention is adapted to retain the key when not in locked position thus preventing the same from being misplaced. 60

It will be observed upon reference to the accompanying drawings that the key engaging member 16 is desirably constructed in the form of a snap hook, the advantage being that the same can be manufactured separately and provided with the openings 70 for accommodating the ring member 10 to provide the improved key fastener, the primary advantage of the device being the peculiar arrangement of these two parts namely, the members 10 and 16 for detachable engagement respectively with the door knob and a key when in a locked position, 75 for preventing the surreptitious movement of the key to an open position.

It will now be apparent that I have devised 80 a novel and useful construction as a key fastener, which embodies the features of advantage enumerated as desirable in the statement of the invention and the above description, and while I have, in the present 85 instance, shown and described the preferred embodiment thereof which was found in practice to give satisfactory and reliable result, it is to be understood that the same is susceptible of modification in various particulars, without departing from the spirit or scope of the invention or sacrificing any of its advantages. 90

Having thus described my invention, what I claim as new and desire to secure by Letters 95 Patent, is:

A key retainer including a spring ring adapted for detachable engagement with the shank of a door knob, a key engaging member including a barrel-like body portion the 100

upper part of which is formed with an opening for accommodating the ring to consequently suspend the engaging member from the ring, a hook formed on the opposite 5 terminal of the body portion and adapted to engage the eye of a key, and a spring pressed

pawl slidably mounted in the body portion for removably closing the hook.

In testimony whereof, I affix my signature hereto.

PAUL T. ULRICH.
